[57] CLAIM

The ornamental design for a portable computer, as shown and described.

DESCRIPTION

FIG. 1 is a front, top and right side perspective view of a portable computer showing our new design;

FIG. 2 is a front elevational view thereof;

FIG. 3 is a right side elevational view thereof;

FIG. 4 is a top plan view thereof;

FIG. 5 is a left side elevational view thereof;

FIG. 6 is a rear elevational view thereof;

FIG. 7 is a bottom plan view thereof;

FIG. 8 is a front, top and right side perspective view thereof being shown in the closed position;

FIG. 9 is a front, top and right side perspective view thereof being shown in the opened position with the keyboard removed from the base.

FIG. 1

FIG. 2

*FIG. 3**FIG. 4**FIG. 5*

FIG. 6

FIG. 7

FIG. 8

FIG. 9
